(57) **CLAIM**

The ornamental design for the seafood shears, as shown and described.

DESCRIPTION

FIG. 1 is a left side perspective view of an ornamental design for the seafood shears of the present invention;

FIG. 2 is a left side view thereof;

FIG. 3 is a top-down view thereof;

FIG. 4 is a bottom-up view thereof;

FIG. 5 is a front view thereof; and,

FIG. 6 is a rear view thereof.

The broken line portions of the figure drawings are included to show portions of the article that form no part of the claimed design.
